UNITED STATES PATENT OFFICE.

GEORGE A. STEINER, OF SALT LAKE CITY, UTAH, ASSIGNOR TO STEINER SALES COMPANY, OF SALT LAKE CITY, UTAH, A CORPORATION OF UTAH.

ATTACHMENT FOR TOWEL CABINETS.

Application filed August 30, 1922. Serial No. 585,260.

The object of my invention is to provide means for concealing and protecting the towel until such time as the user desires its delivery to a convenient point for use.

5 A further object is to provide means for regulating the length of the clean towel so delivered to the end that a cabinet can be readily adapted for delivering varying lengths of clean towel.

10 Other objects of the invention will appear from the following detailed description:

The invention consists generally in various constructions and combinations all as hereinafter described and particularly pointed 15 out in the claims.

In the accompanying drawings forming part of this specification,

Figure 1 is a vertical sectional view through a towel cabinet showing my invention applied thereto.

Figure 2 is a side view of the lower portion of the cabinet showing the curtain or guard device and the mechanism for operating it.

25 Figure 3 is a sectional view on the line 3—3 of Figure 2.

Figure 4 is a detail sectional view showing the means for varying the length of clean towel delivered.

30 Figure 5 is a detail view of one of the feed rolls.

Figure 6 is a sectional view on the line 6—6 of Figure 5.

Figure 7 is a modified construction and 35 illustrates one of the feed rolls expanded or enlarged to increase the length of the towel feed.

Figure 8 is a sectional view on the line 8—8 of Figure 7.

40 Figure 9 is a sectional view on the line 9—9 of Figure 7.

In the drawing, 2 represents the side walls of the cabinet, 3, the door in the front thereof, and 4, the plate closing the top of the cabinet.

45 The side walls have guide ways 5 and 5a. Into these guide ways, the towel rolls 6 and 7 for the soiled and clean towels are inserted, the guide ways having an upper horizontal section and an inner vertical section wherein the rolls rest by gravity.

50 8 represents the feed roll for the soiled towel and 9 the corresponding roll for the clean towel, the towel rolls contacting by gravity with the feed rolls and being re-

volved as the feed rolls are revolved to dispense the clean towel from one roll and wind up the soiled portion thereof on the other roll. On one side of the cabinet, a driving belt indicated by dotted lines in Figures 1 and 4 connects one feed roll with the other so that when one feed roll is revolved, a corresponding movement will be imparted to the other roll. On the other side of the cabinet, the lower feed roll is provided with a loosely mounted sprocket wheel 10 which has a ratchet connection at 11 with the feed roll, so that when the sprocket is revolved in one direction, the feed roll will be moved also, but the sprocket wheel will be free to 60 revolve in another direction without affecting the feed roll. This ratchet device consists of the usual tooth-engaging members, one of them spring actuated, and the other connected with the sprocket wheel as shown in Figure 3. And as it is a common type of ratchet feed, I do not illustrate or describe it more in detail herein. A stud 12 is mounted on the wall of the cabinet and an idle sprocket wheel 13 is mounted thereon 65 and connected by a sprocket chain 14 with the wheel 10. A sheave 15 is secured to the sprocket wheel 13 to rotate therewith, and a tension spring 16 is connected with said sheave and the side wall of the casing. This 70 spring is put under tension when the sheave is rotated for the purpose of returning the sheave and sprocket to their normal position when released. A cord 17 is connected to the sheave 15 and extends down to a treadle 18 mounted at a suitable point on the floor beneath the cabinet. Normally, the tension of the spring 16 will wind the cord on the sheave and hold the treadle in its raised 75 position as indicated in Figure 2.

A bar 19 extends across the open lower end of the casing, and a guard 20 is provided at the rear of the casing pivoted at 21 at a point above the soiled towel roll and depending in the rear of the towel roll and provided at 80 its lower end with a shelf 22 which cooperates with a flange 23 on the bar 19 to close the opening in the bottom of the cabinet and prevent access thereto.

85 Suitable guards 24 preferably of wire mesh, form vertical continuations of the side walls of the cabinet, and protect the towel from access thereto at the sides. A space between these guards is provided at the front of the cabinet through which the user 90

may reach, and draw the clean portion of the towel out to a point where it can be conveniently used as indicated by dotted lines in Figure 1. For the purpose of closing this space or opening when the cabinet is not in use, I provide a roll 25 within a suitable housing 26 at the front of the cabinet, and having a sprocket 27 that is engaged by the belt 14. A flexible curtain 27 is wound on the roll 25 and normally depends between the wire guards for the purpose of concealing the depending clean portion of the towel, and protecting it from dust and dirt or from being handled by inquisitive persons standing in front of the cabinet.

When a person wishes to use the cabinet, he will place his foot upon the treadle 18 and depress it. The sheave 15 will thereby be revolved and the feed rolls will be actuated to deliver a section of clean towel from one roll and wind up the soiled towel on the other roll. At the same time, the sprocket wheel 27 will be revolved to wind up the curtain 27 and expose the space beneath the cabinet and allow the user to reach in and pull out the clean towel to a point where it can be conveniently used. As soon as the user removes his foot from the treadle, the spring 16 put under tension by the depression of the treadle will return the sprockets to their normal position and drop the curtain in front of the clean towel to the position shown in Figure 1. During this return movement, the feed rolls will be stationary, through the ratchet feed connection of the sprocket wheel 10 with the lower feed roll and the position of the towel will therefore be unaffected during this return movement of the sprockets and the lowering of the curtain to its normal position in front of the towel.

It is sometimes desirable to vary the length of feed or the length of toweling to be used in a cabinet. Normally, this is governed by the diameter of the feed rolls; and I, therefore, provide means for varying the diameter of such rolls to the end that the length of their peripheral surfaces may be increased or decreased to effect an increasing change in the length of feed of the towel.

Referring now to sheet 2 of the drawings, I have shown the shafts of the feed rolls provided with a hub 28 having a flange 29 thereon in which slots 30 are formed to receive screws 31 which fit into the ends of the feed roll sections and hold them in their proper relative position. Upon loosening these screws, the feed roll sections may be adjusted toward and from each other to decrease or increase the length of the peripheral surface of the feed roll and thereby vary the length of feed of the towel. In Figures 7, 8 and 9, I have shown a modified construction which consists in mounting a plate 32, on the shaft of the feed roll having

radial slots 33 therein to receive screws 34 which are inserted through said slots and into the ends of the feed roll sections in the manner described with reference to Figures 5 and 6. A recess or seat 35 is provided in each end of the roll to receive the plates 32 as shown in Figure 9, their function being to prevent the halves of the roll from turning on the screws 34 while the diameter of the roll is being adjusted. These feed rolls are equipped with the usual roughened surfaces 36 consisting of sand paper, rubber or other suitable material which will grip the surface of the towel and insure the revolution of the rolls to feed the clean towel from one roll and wind up the soiled portion thereof on the other roll.

I claim as my invention:

1. A towel cabinet comprising clean and soiled towel rolls, feed rolls contacting respectively with said clean and soiled towel rolls and adapted to feed a loop of the clean towel and normally maintain the same in a depending position within convenient reach of the user, a curtain normally concealing the clean loop of towel, a roller for supporting the curtain, and an endless operating means connecting said rollers and said last mentioned roller whereby, when said rollers are operated, said curtain will be withdrawn from in front of said loop.

2. A towel holder comprising a support for clean and soiled towel rolls, a loop of the clean towel normally depending within convenient reach of the user, mechanism operated by the user for feeding the clean towel to a position for use, a guard on either side of the depending loop, and a curtain in front of said loop normally preventing access to the clean loop of towel, and means for automatically rolling up the curtain by the operation of the feed mechanism to allow access to the towel when said feeding mechanism is operated.

3. A towel holder comprising a support for a roll of clean toweling, a feed roll mounted for contact with the towel to feed it from the roll, said feed roll including a hub portion, a hub axle and a ratchet between the hub portion and the axle, a longitudinally divided portion forming two portions, and means for adjusting the divided portions toward and from each other to decrease or increase the diameter of the roll and thereby vary the length of feed of the towel with each revolution of said roll, and mechanism within control of the towel user for oscillating the axle and thus revolving the feed roll.

4. A towel holder comprising a support for clean and soiled towel rolls, feed rolls for said towel rolls, having a driving connection between them, a curtain roll and curtain therefor, normally depending in front of the loop of clean toweling, a sheave having

a ratchet connection with one of said feed rolls, an operating cord for said sheave, and means actuated when a pull of the user is applied to said cord for revolving said feed rolls and curtain roll to wind up said curtain and expose the clean towel, and means for returning said sheave and curtain roll and unwinding said curtain when the user releases said cord.

5 5. A towel holder comprising a support for a roll of clean toweling, a feed roll mounted for contact with the towel to feed it from its roll and having a peripheral surface of greater length than the width of the 10 towel web, said feed roll being composed of longitudinally divided sections extending from end to end thereof and hubs having radial flanges and slots therein, and screws 15 adjustable in said slots and engaging the 20 ends of said sections for increasing or decreasing the diameter of said roll and thereby changing the length of feed of the towel, an axle having thereon a ratchet connection to the hub, and means within control of the 25 user for oscillating the said axle to cause the

feed roll to feed the towel in one direction only.

6. A towel holder comprising a support for the clean and soiled towel rolls, feed rolls having a driving connection between them and contacting respectively with said clean and soiled towel rolls and having peripheral surfaces of greater length than the width of the towel web, said feed rolls being composed of longitudinally divided sections extending from end to end thereof. 30 and means for adjusting said sections toward and from one another to decrease or increase the diameter of the feed rolls and thereby vary the length of the clean towel 35 delivered, said sections having between them at one end a hub, an axle and ratchet connections between the axle and hub, and mechanism actuated by the user of the clean towel for oscillating the axle to cause said 40 feed rolls to feed the towel in one direction. 45

In witness whereof, I have hereunto set my hand this 22nd day of August 1922.

GEORGE A. STEINER.
